UNITED STATES PATENT OFFICE.

EDWARD H. KIMBALL, OF GLENCOE, ILLINOIS.

LOCKING DEVICE FOR TRANSOM-RODS.

SPECIFICATION forming part of Letters Patent No. 687,431, dated November 26, 1901.

Application filed December 14, 1900. Serial No. 39,884. (No model.)

To all whom it may concern:

Be it known that I, EDWARD H. KIMBALL, a citizen of the United States, residing at Glen-
5 coe, in the county of Cook and State of Illi-
nois, have invented certain new and useful
Improvements in Locking Devices for Tran-
sion-Rods and the Like, of which the follow-
ing is a specification.

My invention relates to improvements in
10 devices for automatically locking rods against
movement in the direction of the length
thereof and is particularly adapted for use as
a locking device for transom-rods.

The object of my invention is to provide
15 such a lock which will normally and auto-
matically hold the rod passing therethrough
in locked position, but which may be released
by a movement of the rod itself in the direc-
20 tion of the clamping device, so that with one
hand and with practically one movement of
the hand a transom-rod, for instance, may be
released, moved to the desired point, and au-
25 tomatically locked, whereas with all previous
devices of which I have any knowledge it has
been necessary to release the rod with one
hand and then while holding the lock out of
30 engagement with the rod to move the rod
with the other hand.

In addition to the obvious advantages at-
35 tending my improvement I also by my con-
struction produce a lock characterized by
simplicity and economy in construction as
well as efficiency and convenience in opera-
tion.

These and such other objects as may here-
inafter appear are attained by the device
35 illustrated in the accompanying drawings, in
which—

Figure 1 indicates a plan view of a blank
40 from which the base-plate of my improved
lock may be formed of one piece of metal.
Fig. 2 is a perspective view of the blank
shown in Fig. 1 with the side pieces bent up
so as to form the base-plate for my device.

45 Fig. 3 is a perspective view of one of the
clamping-arms. Fig. 4 is a perspective view
of the other clamping-arm. Fig. 5 is a lon-
gitudinal sectional view through my device,
50 showing the clamping-arms pushed back
against the base-plate and in unlocked posi-
tion. The dotted lines show the parts in nor-
mal position with the rod locked. Fig. 6 is a

perspective view of my complete device.
Figs. 7 and 8 show modified forms of my lock
made in one piece of spring metal.

55

Similar letters of reference indicate the
same parts in the several figures of the draw-
ings.

Referring by letter to the accompanying
drawings, A indicates a sheet of metal pro-
vided with the wings a a'. These wings, pref-
erably in the form of a triangle, as indicated,
are to receive the pivot upon which the clamp-
ing-arms hereinafter referred to are mounted.
These wings are bent substantially at right 65
angles to the body of the plate A, thereby
forming the sides of the base-plate. The por-
tions of the base-plate above and below the
wings or side pieces a a' may be provided with
screw-holes, as indicated, for the passage of 70
screws for the attachment of the base-plate
to a door-jamb or other convenient place. B
and C are oppositely-disposed clamping-arms,
each provided with a bent-up or angular end
b c, which ends are perforated for the passage 75
of the transom or other rod to be locked.
These perforations should of course be
slightly larger in diameter than the diameter
of the rod.

The ends of the arms B and C opposite to 80
the perforations therein may be provided with
lugs or ears b' c', as shown, or may be other-
wise conveniently pivoted to the base-plate.
In my preferred construction the pivoted ends
of these arms are formed so as to interlock in 85
such a manner that they are mounted upon
a common pivot and are both actuated by the
same coil-spring which is mounted on said
pivot, but of course this specific form is not
essential to the spirit of my invention.

90

D is a coil-spring mounted upon the pivot
E, the ends of which spring are so disposed
with relation to the arms B and C, respec-
tively, that said arms are normally forced
away from the base-plate and toward each 95
other, as shown in dotted lines in Fig. 5.

F is a rod, such as the operating-rod of a
transom-lift, which passes through the perfo-
rations in both of said clamping-arms.

The operation of my device is as follows: 100
The rod having been inserted through the
perforations in the locking-arms in a manner
well understood, upon releasing the rod F the
spring D forces the arms B C to swing out-

wardly from the base-plate A and in a direction toward each other, whereby the angular portions *b c* are caused to stand inclined at an angle toward each other, and the opposite edges of the perforations are caused to engage or bite the rod F, thereby securely holding the same locked in position, as shown in dotted lines in Fig. 5. To release the rod, it is only necessary to push it in the direction of the base-plate, whereupon the arms B C are simultaneously forced backward against the spring-pressure until they reach the release position, when, holding the rod in the plane occupied by it when so released, it may be freely moved either way in the direction of its length and when released will immediately become again automatically locked.

To avoid the necessity of care as to the degree of movement of the rod toward the base-plate necessary to release the rod, I prefer to form the arms B C in such a manner that when they reach the release position the bent corners thereof shall be in contact with the base-plate A, thereby forming a stop.

In Figs. 7 and 8 I have shown my lock constructed of one piece of spring metal, in which the arms are normally sprung into the locking position. The operation of the device when so constructed is essentially the same as when the arms are constructed separately and actuated by a separate spring or springs.

It is obvious that the only object of providing two arms is to lock the rod against movement in either way along the direction of its length. If it is only desired to lock a vertical rod against downward movement, as is often the case with a transom-rod, where the transom is merely held in position for purposes of ventilation, it is apparent that the locking-arm B used alone will answer this purpose effectively, and in that event the force of gravity tending to draw the arm B in a downward and outward direction will keep it normally in the position shown in dotted lines in Fig. 5 without the intervention of a spring.

Of course my device is susceptible of various modifications, such as using any of the forms of base-plates well known in this art in place of the base-plate shown and described

herein or providing other forms of springs for actuating the arms B C or mounting said arms separately and providing them with a separate actuating-spring; but such modifications do not constitute a departure from the spirit of my invention and are contemplated as a part thereof.

I claim—

1. A clutch or locking device for transom-rods and the like, comprising a base, two oppositely-disposed perforated angular clamping-arms pivoted to said base, means mounted upon said base for yieldingly forcing said arms toward each other, and a rod passing through said arms and normally clamped thereby, all combined substantially as described.

2. The combination with a transom and its opening attachments, of a base, a pair of spring-actuated arms mounted upon a base, a transom-lift rod passing through holes in said arms, said arms being thrown toward each other by said spring action, so as to engage and lock said rod, and being forced away from each other so as to release said rod by the movement of the rod in the direction of said base, substantially as described.

3. The combination with a transom and its operating-rod, of a base-plate, a pair of hinged clamping-arms mounted on said base-plate, a coil-spring mounted upon the pivot upon which said arms are hinged and actuating said arms toward each other, a rod passing through perforations in said arms and normally locked thereby, substantially as described.

4. The combination with a transom and its operating-rod, of a base, a clamping-arm hinged to said base, a coil-spring mounted upon the pivot upon which said arm is hinged, and normally holding said arm in locking position, said rod passing through a perforation in said arm and normally locked thereby, all so combined that said rod may be released by forcing said arm toward said base-plate, substantially as described.

EDWARD H. KIMBALL.
